M.D.

UNITED STATES PATENT OFFICE.

GEORGE HETHERINGTON, OF PHILADELPHIA, PENNSYLVANIA.

SOUND-BOX FOR TALKING-MACHINES.

1,339,337.

Specification of Letters Patent.

Patented May 4, 1920.

Application filed July 25, 1918. Serial No. 246,690.

To all whom it may concern:

Be it known that I, GEORGE HETHERINGTON, a citizen of the United States, residing at Philadelphia, in the State of Pennsylvania, have invented a certain new and useful Improvement in Sound-Boxes for Talking-Machines, whereof the following is a specification, reference being had to the accompanying drawing.

10 My invention may be included in sound boxes for either gramophones or graphophones, with the object and effect of improving both the volume and quality of the tone reproduced by such machines.

15 It is the object of my invention to provide a sound box with means for bodily adjusting a diaphragm therein toward and away from the tone outlet, and, means for varying the pressure under which the diaphragm is secured at its perimeter.

20 I find it convenient to illustrate my present invention in connection with a sound box having stylus lever mechanism of the type claimed in my application serial 25 177,644 filed June 29, 1917, for Letters Patent of the United States, because, in such embodiment, the means for adjusting the diaphragm as herein disclosed, also enable the operator to vary the pressure of the 30 stylus lever upon the diaphragm and thus permit precise adjustment of the damping effect of the lever mechanism upon the diaphragm. However, it is to be understood that my improved diaphragm adjusting 35 mechanism herein claimed may be embodied in sound boxes which are not provided with lever mechanism of that specific character.

35 In the drawing; Fig. I is a front elevation 40 of a sound box conveniently embodying my improvements.

Fig. II is a central vertical sectional view of said sound box.

Fig. III is a rear elevation of said sound 45 box.

Fig. IV is an inverted plan view of said sound box with the lever mechanism omitted, to show the spring seat upon the box frame.

50 In said figures; the sound box includes the circular tubular frame 1 having the circumferential series of screw threaded holes 2 and the spring seat lug 3 including the plane faced recess 5, at right angles to the 55 axis of said frame. The two nut rings, 7 and 8, are respectively fitted upon axially

opposite sides of said frame 1, and have holes 9 through them in registry with said holes 2 in said frame 1. Said nut 7 has the recessed annular seat 11 in its face remote 60 from said frame 1, to receive the tubular outlet member 12 which has the flange 13 fitted to said recess. Said member 12 also has the flange 14 extending into said box frame 1, in spaced relation with the internal diameter of said frame, and has the cylindrical tubular shank 15 opening into the conical recess 16, which is concentric therewith, and has its base toward said frame. The radial stud 17 is provided on 65 said shank for engagement with a slot in a tone arm, to determine the precise position of the sound box with reference to said arm. The screws 19 extend through said flange 13 of said outlet member 12, and 70 through said recessed nut 7, into engagement with said holes 2 in said frame 1. The screws 20 extend through said other nut 8, and into engagement with said holes 2 in said frame 1; whereby said frame, nuts 80 and outlet member may be rigidly connected. The two adjustable clamping rings, 21 and 22 have screw threads upon their perimeters respectively fitted through said nuts 7 and 8. The diaphragm 24, which may 85 be formed of a plane sheet of mica or may be of any suitable form and material, is fitted in said frame 1, intermediate of said two clamp rings 21 and 22, and the two resilient gaskets, 26 and 27, are located upon 90 respectively opposite sides of said diaphragm and interposed between the latter and the respective clamping rings 21 and 22; whereby said diaphragm is resiliently held at its circumferential margin, and under 95 adjustably variable pressure, between said gaskets, such pressure being variable by rotary adjustment of said clamping rings in respective screw threaded engagement with said nuts. Such adjustment may be conveniently effected by engagement with the notches 28 or other suitable wrench holds upon said rings, and determines not only 100 the pressure applied to the diaphragm, but the position of the latter axially in said frame. Said gaskets 26 and 27 are conveniently formed of cut lengths of cylindrical soft rubber tubing, bent to circular form, to fit said frame 1. However, it is to be understood that they may be otherwise 105 formed.

However, as said lever (which is merely

a convenient form of spring held stylus bar) is continuously maintained in operative relation with the diaphragm, by its pressure thereon, it is unnecessary to thus cement or otherwise unite them at their junction. The stylus lever 29 extends radially with respect to said frame 1 and has its inner end attached to said diaphragm 24, conveniently by cement 30. The stylus socket 31 is rigidly connected with the outer end of said lever 29 and has plane faced lugs 32 forming spring seats, upon opposite sides thereof, substantially parallel with the spring seat 5 in said frame, and has the set screw 34, to detachably engage a suitable stylus 35. The two flat springs 36 extend upon respectively opposite sides of said stylus socket 31 and have their opposite ends respectively connected with said frame and with said socket, by the screws 37 and 38. Said springs 36 are preferably constructed and arranged to resiliently press said diaphragm toward said outlet member by said lever; the degree of such pressure being variable in accordance with the axial adjustment of said diaphragm, effected by adjustment of said clamping rings.

However, it is to be understood that if the springs aforesaid be omitted, as they are in many ordinary forms of sound boxes, to which my improved diaphragm adjusting mechanism aforesaid may be applied; movement of the clamping means may not vary the co-operative relation of the stylus lever and diaphragm, as far as any damping effect upon the diaphragm by said lever is concerned.

My diaphragm adjusting mechanism above described is advantageous as compared with ordinary sound boxes, having an abutment upon one side of the diaphragm to support the perimeter of the latter, in that any attempt to adjust the pressure of the gaskets upon a diaphragm supported by a stationary abutment necessarily changes the axial position of the diaphragm in the sound box in accordance with the degree of compression of the gasket interposed between the diaphragm and such abutment. On the contrary, in my improved structure above described, the pressure of the gaskets upon the diaphragm may be varied without shifting the diaphragm axially in the sound box; because, the diaphragm is supported between opposite abutments formed by clamping rings which are both adjustable axially in said box. Such capacity for adjustment is important as the precise location of the diaphragm materially affects its efficiency of transmission of sound vibrations with respect to the outlet.

My diaphragm adjusting mechanism above described is further advantageous as compared with the ordinary mechanism in that the pressure upon opposite sides of the

diaphragm 24 may be adjustably varied by pressing said clamp rings 21 and 22 toward each other, while in contact with the resilient gaskets 26 and 27, without turning said rings; not only because it is difficult to turn 70 said rings when in frictional engagement with said gaskets, under such pressure as is necessary for holding said diaphragm, but because any such turning movement would tend to displace said gaskets from their desired position and thus interfere with the intended operation of said diaphragm. It may be observed that this feature of my invention is dependent upon the fact that the nut rings 7 and 8 are respectively separate 75 from the circular tubular frame, 1 of the sound box and independently axially adjustable with respect thereto as above described. That is to say; said clamp rings 21 and 22 may be independently axially adjusted in 80 their respective nut rings 7 and 8 with said members 1, 7 and 8 detached from each other and, said clamp rings be thereafter pressed together to the position shown in Fig. II by means of said screws 19 and 20; said frame 90 1 of course serving as an abutment precisely limiting the extent of approach of said nut rings 7 and 8.

Although I have shown an outlet member provided with a conical recess immediately 95 adjoining the diaphragm; it is to be understood that such construction is not of the essence of my invention.

Therefore, I do not desire to limit myself to the precise details of construction and arrangement herein set forth, as it is obvious that various modifications may be made therein without departing from the essential features of my invention as defined in the appended claims.

I claim:

1. The combination with a spring held stylus bar; of a diaphragm operatively related thereto and mounted so as to be shifted axially in different planes.

2. The combination with a spring held stylus bar; of a diaphragm operatively related thereto; and a mounting for said diaphragm, whereby it may be shifted axially in different planes, including a tubular frame encircling said diaphragm; independently axially adjustable rings on said frame upon respectively opposite sides of said diaphragm; and means, on said frame, arranged to axially shift said rings toward each other without turning them.

3. The combination with a spring held stylus bar; of a diaphragm operatively related thereto; a mounting for said diaphragm, whereby it may be shifted axially in different planes, including a tubular frame encircling said diaphragm; two separable nut rings, upon respectively opposite sides of said diaphragm, each having an internal screw thread concentric with said dia-

phragm; two clamp rings, independently axially adjustable upon respectively opposite sides of said diaphragm, each having an external screw thread and fitted to said respective nut rings; and means, independent of said screw threads, arranged to press said rings toward each other without turning them.

In testimony whereof I have hereunto signed my name at Philadelphia, Pennsylvania, this thirteenth day of July, 1918.

GEORGE HETHERINGTON.

Witnesses:

ARTHUR E. PAIGE,
CAROLYN E. REUTER.

It is hereby certified that in Letters Patent No. 1,339,337, granted May 4, 1920, upon the application of George Hetherington, of Philadelphia, Pennsylvania, for an improvement in "Sound-Boxes for Talking-Machines," errors appear in the printed specification requiring correction as follows: Page 1, line 112, commencing with the word "However" strike out all to and including the word and period "junction.", page 2, line 5; page 2, line 9, after the period insert the sentence:

"However, as said lever (which is merely a convenient form of spring held stylus bar) is continuously maintained in operative relation with the diaphragm, by its pressure thereon, it is unnecessary to thus cement or otherwise unite them at their junction.;

and that the said Letters Patent should be read with these corrections therein that the same may conform to the record of the case in the Patent Office.

Signed and sealed this 25th day of May, A. D., 1920.

[SEAL.]

M. H. COULSTON,
Acting Commissioner of Patents.
